UNITED STATES PATENT OFFICE.

MARSHALL L. SHEPHERD, OF MONTGOMERY, ALABAMA, ASSIGNOR TO SHEPHERD AUTOMATIC SWITCH COMPANY, INC., OF MONTGOMERY, ALABAMA, A CORPORATION OF ALABAMA.

RAILWAY-SWITCH MECHANISM.

1,172,172.

Specification of Letters Patent. Patented Feb. 15, 1916.

Application filed April 2, 1915. Serial No. 18,752.

To all whom it may concern:

Be it known that I, MARSHALL L. SHEPHERD, a citizen of the United States, residing at Montgomery, in the county of Montgomery and State of Alabama, have invented new and useful Improvements in Railway-Switch Mechanism, of which the following is a specification.

This invention relates to railway switch mechanism for controlling the passage of rolling stock from a main track to a branch track or siding, and vice versa, and constitutes certain improvements upon the type of switch mechanism shown in my prior 15 United States Letters Patent No. 1,079,889, dated Nov. 25, 1913.

One object of the present invention is to provide a switch mechanism embodying a novel construction, arrangement and organization of parts, whereby certain advantages in point of increased efficiency and greater reliability are obtained.

Another object of the present invention is to provide certain improvements in the switch throwing and locking devices which insure certainty of action under all conditions of service.

Still another object of the invention is to provide a compensating connection between the switch point and switch throwing and locking mechanism, which connection is adapted to reduce shocks and jars, take up and compensate for wear and spreading of the rails, and to positively prevent locking 35 of the switch point in a partly closed position.

With these and other objects in view, which will appear as the nature of the invention is better disclosed, the invention consists of the features of construction, combination and arrangement of parts, herein-after fully described and claimed, reference being had to the accompany drawings, in which:—

45 Figure 1 is a top plan view of the rails and switch mechanism at a switch point, showing the switch point locked in normal position for travel on the main line. Fig. 2 is a top plan view of parts of the switch mechanism on an enlarged scale, and in the position they occupy when the switch is locked in closed position. Fig. 3 is a view in side elevation of the parts shown in Fig. 2. Fig. 4 is a section on line 4—4 of Fig. 2. 55 Fig. 5 is a section on line 5—5 of Fig. 2.

Fig. 6 is a section on line 6—6 of Fig. 2. Fig. 7 is a perspective view of the throw-bar and sliding actuating bar. Fig. 8 is a view similar to Fig. 2, showing positions of the parts of the switch mechanism when the switch is locked in open position. Fig. 8^a is a detail section on the line 8^a—8^a of Fig. 8. Fig. 9 is a section on line 9—9 of Fig. 8. Fig. 10 is a perspective view of some of the parts. Fig. 11 is a top plan view showing the motion transmitting connection between the actuating rod and the switch point. Fig. 12 is a section on the line 12—12 of Fig. 11. Fig. 13 is a top plan view showing one of the motion transmitting connections between the guard rail and actuating rod. Fig. 14 is a section on line 14—14 of Fig. 1. Fig. 15 is a perspective view of the pivoted latch or locking device. Fig. 16 is a section on line 16—16 of Fig. 13. Fig. 17 is a top plan view showing a modification in the construction of the switch mechanism. Fig. 18 is a section on line 18—18 of Fig. 17. Fig. 19 is a section on line 19—19 of Fig. 17. Fig. 20 is a perspective view of the latch or locking device shown in Fig. 17. Fig. 21 is a similar view of the trip yoke employed in connection therewith.

Referring to Figs. 1 to 16, inclusive, of the drawings, 1 and 2 designate the main line rails, 3 and 4 the branch line or siding rails, and 5 and 6 the switch rails connected for movement in unison by the rod 7, said rails 5 and 6 forming a switch point movable laterally to open and close communication between the main and branch lines. The switch point is self-closing, being normally held in closed position for travel over the main line by a controlling device 8, shown in Figs. 11 and 12, and the construction and operation of which will be herein-after fully described. In the present instance I have not shown any means for automatically throwing the switch from the main line, but an automatic switch mechanism for this purpose of any suitable construction or of the type shown in my prior patent hereinbefore referred to may be employed. A switch throwing and locking mechanism is arranged at one side of the track structure and in proper proximity to the switch point, and comprises a sliding switch throwing and controlling bar 9, movable in a direction laterally or transversely of the rails. This bar 9 has its inner end 100

terminating adjacent to the point of junction of the rails 2 and 4 and formed to provide a chamber 10 having an inner end wall 11 provided with a guide opening 12, and 5 having an outer end wall 13 provided with a slot or opening 14. The chamber 10 and slot 14 are open at one side to receive the stem portion 15 of a connecting rod 16, the extremity of which stem portion slidably 10 engages the opening 12 while the body of the rod extends through and slidably engages the slot 14. A head 17 is provided upon the stem for abutment against the wall 13 to limit the outward sliding movement of the rod, the body of which is formed with an eye 18 pivotally connected with an eye on the adjacent end of the rod 7, which moves through an opening in the flange of the rail 2, thereby coupling the rod 7 and 15 rod 16 for conjoint motion. The stem 15 is threaded for a portion of its length to receive a nut 20, and surrounding said stem between the wall 11 and nut 20 is a coiled cushioning and compensation spring 21, the 20 construction providing a lost-motion, cushioning and compensating connection between the throw rod and switch point, for purposes 25 hereinafter explained.

The rod 9 is provided with a pair of oppositely extending lateral abutment shoulders 22 and 23, located at a point between its ends, and at its forward end is formed or provided with a latch or keeper plate 24 having locking surfaces 25 and 26, and at its 30 rear end the rod is formed with a short oblong slot 27 and opposite serrated surfaces 28. Arranged for coöperation with the throw bar is a latch or locking device 29, pivoted at a point intermediate of its length 35 to swing horizontally upon a vertical axis 30. The forward or inward arm of this latch or locking device is provided with a lateral locking projection 31 for coöperation with the surfaces 25 and 26 of the plate 24, 40 while the outer or rear arm of the latch is formed with a toe portion 32, having inclined or cam surfaces 33 and 34 and a guide surface 35. Connected with the latch is a bolt or rod 36 slidably engaging a 45 perforated guide bracket 37 and surrounded by a coiled spring 38 interposed between said bracket and an adjustable abutment on the bolt consisting of a washer, adjusting and lock nuts, as shown at 39, whereby the spring 50 38 may be tensioned. This spring is adapted to permit the latch or locking device to have a yielding retractive movement, while serving to normally hold it in locking position.

55 Arranged along the inner side of the rail 4 adjacent to the switch point is a laterally movable, wheel actuated guard rail 40, which is adapted to be forced inwardly a predetermined distance by the flanges of wheels 60 passing over said rail. This guard rail is

suitably mounted for sliding motion and is coupled by connections, consisting of rods 41 and bell crank levers 42, with a longitudinally movable actuating rod or bar 43 arranged outside the rail 4 and reciprocable 70 bodily in a direction parallel therewith. The rail 40 is self-closing, being normally held in contact with the rail 4 by spring controlled retracting devices, each consisting of a rod 44 connected with one arm of a laterally swinging lever 45 pivoted at its opposite end to a bracket 46, the lever being connected, at a point between its transverse center and pivoted end, with one end of a plunger rod 47 slidably mounted in a fixed 80 casing 48 and acted upon by a spring 49 inclosed within said casing and adapted to be tensioned by nuts 50. A suitable number of these spring controlled retracting devices are employed, and the combined pressure 85 due to the expansion of their springs is utilized to normally hold the rail 40 closed against the rail 4, while permitting it to have yielding spreading motion away from said rail 4 under the pressure of the wheel flanges, and to return the guard rail to closed position when the pressure of said flanges is removed. By employing pivoted levers 45 between the rail 40 and the spring plungers, the longer arms of which levers are connected with the guard rail, it will be evident that the travel of the plungers is reduced with respect to that of the guard rail, so that while the springs will be compressed to a certain and sufficient degree to return the 90 guard rail to normal position, their compression will not be compounded or carried out to such a degree as to render them unduly resistant against switch throwing motion of the guard rail and the actuating rod 43. 95

A spring retracting and compensating connection is also provided between the rail 6 of the switch point and the actuating rod or bar 43, and this connection comprises a rod 47' attached at one end to the rail 6 100 and slidable through the flange of the rail 4 and pivotally coupled at its opposite end to one end of a lever 48'. This lever 48' is pivoted at its opposite end for lateral swinging motion to a bracket 49' and at 105 an intermediate point is coupled to a plunger rod 50', slidable within a casing 51 and through a nut or closure plug 52 at the inner end of said casing. A coiled spring 52 surrounds the rod within the casing between the 110 plug or closure 52 and adjusting and check nuts 54 on the rod, whereby the spring may be tensioned, a nut 55 being applied to the outer end of the rod and serving to limit its inward motion with respect to the casing. 115 The casing is fitted to slide within a guide housing 56 secured to the track foundation and is pivotally connected at its opposite end with one arm of a bell crank lever 57, the other arm of which has a lost-motion 120

connection with the actuating rod or bar 43. This lost-motion connection may be of any suitable form, but, as shown, consists in providing the other arm of the lever 57 with a forked end 58 engaging the rod 43 between spaced shoulders 58^a and 58^b thereon, the normal positions of which are as shown in Fig. 11.

The parts just described form a telescopic spring controlled connection between the actuating device and switch point, which serves to always return the switch point, after actuation and release, to normal position, and which insures a smooth and reliable cushioning action and further permits independent motion of the actuating rod in certain phases of operation, the parts further serving in such action as a lost-motion connection.

20 The forward end of the actuating rod or bar 43 is coupled by a pair of toggle-jointed levers 59 to the short arm of a motion transmitting lever 60, pivotally supported, as at 61, to swing in a direction laterally of the 25 trackway and carrying at the free end of its long arm an adjustable friction contact roller 62, adapted to engage the shoulder 22 of the bar 9 to transmit switch throwing motion to the latter when the actuating bar 30 43 is operated in switch throwing direction by the guard rail 40.

Pivoted at one end, as at 63, to the long arm of the lever 60 is a latch controlling member in the form of a bar or lever 64, which normally lies parallel with the lever 60 and is held in such position by a coiled spring 65 disposed upon a bolt or rod 66 connected with the lever 64 and having a sliding engagement with the lever 60 and 40 provided with a nut 67 whereby the spring may be tensioned. This spring is stiff enough to return the lever 64 to normal position after outward movement, and upon its release for retraction, and yet light 45 enough to permit the lever 64 to separate or swing outward from the lever 60 for latch controlling actions, as hereinafter described. The free end of the lever 64 carries an adjustable friction roller 68 which 50 normally seats within the recess or slight concavity formed by the toe portion 32 of the latch or locking device 29, is movable for contact with the cam surfaces 33 and 34 to tilt the latch or locking device to retracted 55 position, and is engageable with the surface 35 of the latch or locking device and adapted to seat in a notch or recess 35' therein to adapt the latch or locking device to maintain a secondary locking position to hold the 60 switch point in thrown position. Pivoted to the lever 60 is a gravity latch dog 69 which is adapted to extend transversely across the levers 60 and 64 when said levers are in parallel relation, one end of said dog being provided with a latch hook 70 to engage and

connect the lever 64 with the lever 60 for retraction, as shown in Figs. 8 and 9. The other end of said dog has a striker arm 71 adapted for engagement with an adjustable contact or abutment 72, whereby when the lever 60 is in normal position, the dog 69 will be held out of engagement with the lever 64 to permit the latter to have independent movement, as shown in Figs. 1, 2, 3 and 4.

75 It will thus be understood that a train running from the branch line into the main line will shift the bar 40 laterally by engagement of the flanges of its wheels with said bar, by which the retracting springs of said bar will be tensioned and the connections 41 and 42 actuated to move the actuating rod or bar 43 longitudinally in a direction toward the branch line, whereby the toggle links or levers 59 will be straightened out to a certain extent, as shown in Fig. 8. As a result the lever 60 will be swung on its pivot 61 until the friction roller 68 of the lever 64 travels inwardly over the cam surface 33, whereby the latch 29 will be tilted 80 to withdraw the projection 31 from engagement with the latch surface 25 so as to release the throw bar 9 and permit the switch point to be thrown. In this motion of the lever 60 the dog 69 is carried out of engagement with the contact 27 and tilts by gravity to lock the two levers 60 and 64 together, and at this time the friction roller 62 of the lever 60 engages the shoulder 22 and operates the throw bar 9 to throw the 85 switch. In this switch throwing movement the friction roller 68 of the trip lever 64 moves beyond the cam surfaces 33 and 34 and engages the recess 35' in the surface 35, allowing the latch 29 to be drawn into locking engagement with the rear locking surface 26 by the action of its spring 38, the switch being thereby thrown and locked in 90 thrown position.

95 When the rod 43 and parts above described are actuated on their switch throwing motion, the spring 21 of the lost-motion and compensation connection between the rod 7 and throw bar 9 serves, first, as a cushioning device to protect the switch point and 100 parts from liability of damage resulting from rapid movement of the bar 20, as when the train or car is traveling at high speed, and, secondly, the spring 21 serves as a motion transmitting connection by which the 105 movement of the bar 9 is communicated to the rod 7 to throw the switch so as to connect the rails for travel between the branch and main lines. This lost-motion and compensating connection also serves a further 110 function in the release and retraction of the switch point, to guard against danger, as hereinafter stated. On the switch throwing motion of the rod 43 the parts of the lost-motion compensating connection between 115

said rod and the switch rail 6 operate as a unit after a preliminary motion of the bar 43 necessary to bring the shoulder 58^a into engagement with the yoke 58, during which 5 preliminary motion of the rod the latch 29 is released to permit the switch point to be thrown, as previously described. On the continued movement of the rod 43, whereby the switch point is thrown by the movement 10 of the bar 9, the bell crank lever 57 is operated to shift the casing or sleeve 51 inwardly, in which motion it moves in unison with the rod or stem 50', owing to the connection afforded by the engagement of the 15 closure 52 with the nut 55, whereby the throw motion of the switch point is permitted and additional power obtained through the connection just described. When, however, the switch point is unlocked for a closing 20 action by the movement of the guard rail 40 by the wheels of a train passing from the branch line into the main line, and while the said switch point is engaged and held open by the wheel flanges after the guard 25 rail 40 has been released and returned to normal position by the springs 49, it will be evident that the spring 53 will remain compressed or under tension, since the guard rail and actuating rod on their return motion restore the part 51 to normal position. The stem 50', however, being held by the 30 open switch point 6 against inward movement, can not move outwardly as a unit with the part 51 to return to normal position 35 until the switch point 6 is released. As a consequence, the guard rail 40 and rod 43, immediately upon release, are returned to normal position by the springs 49, while the switch point is held open until cleared by 40 the wheels and is then closed by the contraction of the spring 53. It will thus be seen that in the operation stated the spring 53 serves to close the switch point.

When the guard rail 40 is released by the 45 wheels and is retracted by the action of its retracting springs, the rod 43 is returned to normal position, and in such motion the shoulder 58^b engages and moves the bell crank lever 57 back to normal position, in 50 which the casing 51 is operated to tension the spring 53, as just described. On such return motion to normal position the rod 53 shifts the toggle levers 59 back to the position shown in Fig. 2, thereby swinging the 55 lever 60 backwardly to normal position, carrying with it the trip lever 64, the friction roller 68 of which engages the cam surface 34 and tilts the latch 29 to released position, thus allowing the parts of the latch 60 controlling mechanism to return to the normal position shown in Fig. 2. In the travel of the train from the branch line to the main line, it will be evident that after the guard rail 40 is released by the wheels the switch 65 point 6 will still be held open by the wheel

flanges and must remain open until the train passes fully beyond the switch point into the main line. The switch point is not locked at this stage in open position, however, as the full retraction of the throw bar 9 is prevented by reason of the fact that the shoulder 17, owing to the switch point being held open by the wheels, opposes resistance to the return movement of the bar 9 beyond a predetermined extent. This return motion 70 is equal only to the distance the bar is permitted to move by the shoulder 17 under the expansion of the previously compressed spring 21, which is just sufficient to bring the keeper plate 24 at its middle point in 75 contact with the projection 31 of the latch bar 29, thereby preventing the full return of the bar 9 and the consequent locking of the switch point in open position, with obvious objections. When, however, the switch 80 point is released by the wheels upon the entry of the train into the main line, the switch point is automatically closed by the action of the springs 49 and 53 and transmits the balance of the return motion to the 85 bar 9, which is again locked in normal or retracted position by the engagement of the latch projection 31 with the shoulder 25. Thus it will be seen that while the train releases the guard rail for an automatic closing 90 action upon the passage of the wheels beyond the same, the switch point will remain held open by the wheels until the switch is fully cleared, the locking device being held inoperative by the action of the 95 lost-motion compensating connection between the switch point and throw bar to prevent said switch point and throw bar from being locked in thrown position, thus insuring a positive and absolutely safe 100 closure of the switch point upon the passage of the train beyond the switch into the main line and avoiding liability of derangement 105 of the switch mechanism and subsequent trouble or accidents.

As before stated, an automatic means, 110 such as shown in my prior mentioned patent, may be employed for controlling the latch and throwing the switch point from the main line, for travel of the rolling stock from the main line to the branch line, the switch mechanism being adaptable for use in conjunction with a train controlled switch throwing device for this purpose. In the present instance, however, I have 115 simply shown a manually operable switch mechanism whereby the switch may be thrown for the travel of rolling stock from the main line to the branch line, and which manually operable switch throwing mechanism may operate without interfering with or interference from the automatic switch throwing mechanism in the branch line. This manually operable switch throwing mechanism comprises a weighted hand lever 120

125 130

73 coupled by a suitable crank connection 74 with a link 75, coupling said crank connection to a sliding actuating bar 76. This bar has a head portion 77 to engage the 5 abutment shoulder 23 of the bar 9 and is provided with a longitudinal slot 78 through which passes the headed end of a connecting pin or bolt 79, which extends through the elongated aperture 27 in the bar 9 and is provided with a flange 80 and a clamping nut 81 serrated to engage the serrated surfaces 28 of the bar 9, whereby the bolt or pin is held in adjusted position upon said bar 9. A check nut 82 is provided to hold 10 the nut 81 from working loose and a washer 83 on the pin or bolt is of suitable form for coöperation with the flange 80 to guide the bar 76 for motion in parallelism with the bar 9. This construction provides a 15 sliding lost-motion connection between the two bars 9 and 76, which permits the bar 9 and latch 29 to be controlled independently of the bar 76 by means of the automatic actuating mechanism in the branch line, and at the same time permits the bar 20 9 and latch device to be controlled by the bar 76 from the hand switch independently of the said automatic actuating mechanism, it being evident that the pin 79 may slide 25 freely in the slot 78 without interfering with the bar 76 when the bar 9 is actuated by the lever 60.

As previously described, the trip lever 64 is normally free for movement independent 30 of the lever 60, owing to the fact that the dog 69 is normally held retracted by the abutment 72. Hence when the bar 76 is moved inwardly or forwardly by the hand lever, it will be obvious that its head 77 35 will engage and move the lever 64 forwardly independently of the lever 60, so that the roller 68 will engage the cam surface 33 and trip and release the latch, so that on the continued forward movement 40 of the bar 76 the head 77 thereof will engage the shoulder 23 and impart switch throwing motion to the bar and from the bar to the switch point through the interconnecting lost-motion and compensation 45 spring connection, the springs 21 being tensioned in such action and the switch point and throw bar 9 being locked in closed position by the engagement of the latch with the shoulder 26. The switch point will thus 50 be held in locked position until the wheels of the rolling stock engage and move the switch rail 40 away from the rail 4, thus actuating the rod 43 to release the latch to 55 permit the switch point to close, the switch point being held open, however, until cleared by the wheels by the pressure of the wheel flanges on the rail 40.

When the rail 40 is moved away from the rail 4 by the wheels of a train passing from 60 the main to the branch line, the rod 43 will

be actuated as previously described and will transfer motion to the lever 60, which in this instance will move forwardly until the dog 69 engages the trip lever 64 and locks said lever 64 to the lever 60 for their retraction as a unit. The parts will remain in this position, in which the latch 29 is disposed in the locking position shown in Fig. 8, until the rolling stock passes the rail 40, whereupon the actuating parts will 70 be returned by their springs to normal position, the levers 60 and 64 being retracted until returned to the position shown in Fig. 2 and in their retraction tripping the latch 75 29 to release the throw bar 9 for the closing of the switch point and moving of said throw bar back to normal position, in which the parts are relocked by the latch 29, thereby resetting the switch to close the main line and for the succeeding switching operation. When the weighted switch lever 73 is released it drops back to normal position, thus retracting and resetting the bar 75. Hence it will be seen that the switch 80 may be thrown by the automatic device in the branch line or by the hand switch mechanism without interference, each from the other, and will be properly controlled and automatically closed or reset upon the travel of the rolling stock past the switch point. 85

In the slightly modified form of my invention shown in Figs. 17 to 21, inclusive, the latch device 29 is pivoted to swing vertically on a horizontal axis 30^a, and the throw bar 9 is provided with a reduced portion or shank 84 providing an abutment shoulder 85. The pivoted actuating lever 60 in this construction has a forked end 86 which loosely engages the shank 84 and is adapted to abut against the forward upright arm 105 87 of a U-shape sliding and tilting trip member or latch controlling slide 64^a having its arms 87 and 88 provided with openings 89 for the passage of the shank 84 which they slidably engage, the upper end of the 110 arm 87 being slotted or bifurcated as at 89^a to receive and engage the trip arm of the latch lever 29, and carrying a friction roller 68^a serving the same function as the roller 68 before described. The slide 64^a is provided with a pair of spaced depending lugs 90, provided with apertures 91 for the passage of a pin or bolt 92, passing through an elongated longitudinal slot 93 in a sliding actuating bar 76^a connected by a crank arm 120 94 with the hand throw lever 73^a, said sliding actuating bar being provided with an inclined or cam surface 95. The upper face of the horizontal body portion of the slide 64^a is grooved, as at 96, to partly receive a 125 dog or latch bar 97 pivoted thereto at 98 at a point between its center and forward end, the rear or longer and heavier arm of said dog or latch bar being movable vertically in a slot 99 in the arm 88 and adjacent 130

end of the body of the slide 64^a and adapted to tilt down into engagement with the cam or inclined surface 95 and to be normally supported by a ledge or shoulder 100 on the bar 76^a adjacent to and in rear of said cam or inclined shoulder. In the operation of these parts through the rod or bar 43 the lever 60 is swung by the straightening out of the toggle levers 59 as before, and its 10 forked end 86 engages and slides the arm 87 of the slide 64^a into engagement with the shoulder 85, so that during the fore portion of the movement of the actuating bar and lever the friction roller 68^a will slide over 15 and beyond the cam faces of the latch 29 and retract said latch, the arm 87 on the continued and remainder of the movement of the bar 43 and lever 60 shifting the bar 9 to switch throwing position in which it is 20 locked by the action of the latch 29 in the same manner as before. In this operation the bar 76^a remains stationary and as the slide 64^a moves forwardly the weighted arm of the latch dog 97 moves past the ledge 25 100 and tilts downward into engagement with the inclined surface 95, thus tilting the forward and short arm of said latch into engagement with the forked end 86 of the lever 60 and coupling the trip member to 30 said lever for subsequent return motion to normal position, as will be readily understood. In the operation of the switch mechanism by the lever 73^a the bar 76^a on its forward movement engages the pin 92 35 and carries the trip member with it, said trip member sliding along the shank 84 and tripping the latch and moving the throw bar 9, but without affecting the lever 60, since in this instance the bar 76^a and trip member 40 move as a unit and the locking dog remains supported by the ledge or shoulder 100, so that the dog slides under the forked arm 86 of the lever 60 to permit the latch and throw bar to be operated without interference 45 from the actuating elements in the branch line.

From the foregoing description, taken in connection with the accompanying drawings, the construction and mode of operation 50 of my improved switch mechanism will be readily understood, and it will be seen that the invention provides a switch mechanism which is adapted to be operated for the passage of rolling stock in either direction from one line to the other, and that the switch can not remain open after passage of a train, but will positively close and remain closed until again actuated, so as to prevent 55 accidents to following trains and thus safe 60 guard the traveling public. It will be further seen that the switch throwing devices are adapted to operate independently 65 of one another and control a common locking means, whereby the construction is simplified and friction reduced, owing to the

minimum number of parts operating at a time. The invention overcomes the well known objections to split and other common types of switches in use, inasmuch as a safe crossing is insured at all times. It will be 70 understood, of course, that the motion transmitting parts of the switch mechanism will be suitably housed and protected from the elements and from accidental injury, as well as from the damage or operation of the 75 switch by malicious persons or intending train wreckers, the construction being such that the switch can only be thrown under ordinary conditions by the power of passing 80 rolling stock.

I claim:—

1. In a railway switch, a self-closing switch point, a switch throwing bar, means for operating said bar, a locking device for locking the bar in switch opening and closing positions, and a lost motion elastic connection between the switch point and bar operative to permit the switch point to be held open by the wheels until cleared after the bar has returned to normal position. 90

2. In a railway switch, a self-closing switch point, a switch throwing bar, a plurality of separate and independent devices for operating said switch throwing bar, a locking device for locking the switch throwing bar in switch opening and closing positions, and a lost-motion elastic connection between the switch point and bar operative to permit the switch point to be held open by the wheels until cleared after retraction 95 of said bar. 100

3. In a railway switch, a self-closing switch point, a switch throwing bar, a plurality of separate and independent devices for operating said switch throwing bar, a locking device adapted to be released prior to the throwing of the switch and set for a relocking action, and a lost-motion elastic connection between the switch point and bar operative to permit the switch point to be held open by the wheels until cleared after 110 retraction of said bar. 110

4. In a railway switch, a self-closing switch point, a switch throwing bar, a train controlled element for operating said bar, a locking device adapted to be released prior to the throwing of the switch and set for a relocking action, and a lost motion elastic connection between the switch point and bar operative to permit the switch point to be held open by the wheels until cleared after 120 the bar has returned to normal position. 120

5. In a railway switch, a self-closing switch point, a switch throwing bar, a switch throwing device, an actuating element operated thereby, switch throwing and locking means controlled by said element and co-operating with the same and the switch bar, and a lost-motion telescopic spring controlled connection between said actuating 130

element and the switch point, said connection comprising parts movable in unison in one direction and independently in the opposite direction.

5 6. In a railway switch, a self closing switch point, a switch throwing bar, a lost motion telescopic spring controlled connection between the switch point and switch throwing bar, a train-controlled switch

10 throwing device, an actuating element operated thereby, switch throwing and locking means controlled by said element and co-operating with the same and switch bar, and a lost-motion telescopic spring controlled 75 connection between said actuating element and the switch point, said connection being composed of parts movable in unison in one direction and independently in the opposite direction.

15 20 7. In a railway switch, a self-closing switch point, a switch throwing bar, a locking device for locking the bar in switch opening and closing positions, a train controlled operating member, an actuating element 75 operated thereby, and a connection between the actuating element and switch point, said connection embodying telescopic members, one connected with the switch and the other having a lost-motion connection 80 with the actuating element, and a spring between said telescoping parts operative to permit the first-named part to have independent movement in the switch opening direction and to subsequently return said 85 part to normal position.

8. In a switch throwing device, a self-closing switch point, a switch bar for operating the same, an actuating element, a motion transmitting member operable by said 100 element, a latch device for locking the switch bar in open and closed positions, and a trip member carried by said motion transmitting member and co-operating therewith to first retract the locking device and then operate the switch bar.

9. In a switch throwing device, a self-closing switch point, a switch throwing bar, an actuating element, a motion transmitting member movable by said element, a trip device pivotally connected with said member, a locking device for locking the switch throwing bar in open and closed positions, said pivoted trip member being adapted to 105 retract the locking device and permit the switch to be thrown, and means for independently operating the trip member.

10. In a railway switch, a self-closing switch point, a switch throwing bar, a train controlled element for actuating said switch throwing bar, a locking device adapted to be released prior to the throwing of the switch and set for a relocking action, a lost-motion elastic connection between the switch point and bar operative to permit the switch point to be held open by the wheels until

cleared after retraction of the bar, and a lost-motion telescopic spring controlled connection between said train controlled element and the switch point, said connection comprising parts movable in unison in one direction and independently in the opposite direction.

11. In a railway switch, a self-closing switch point, a switch throwing bar, a tilting latch for locking the bar in switch opening 75 and closing positions, said latch having a pair of spaced cam surfaces, actuating means for shifting the switch bar to switch opening and closing positions, and a trip device controlled by said actuating means 80 and adapted to engage the cam surfaces of the latch device to tilt said latch device and release the bar for its switch opening and closing movements.

12. In a railway switch, a self-closing switch point, a throw bar having a lost-motion cushioning connection with the switch point, a latch for locking said throw bar in switch opening and closing positions, switch throwing devices, a trip member operable 90 independently by said devices for controlling the latch, and means adapting said trip member to be positively coupled to one of said switch throwing devices for retraction thereby.

13. In a railway switch, a self-closing switch point, a throw bar having a lost-motion cushioning connection with the switch point, a latch for locking the throw bar in switch opening and closing positions, automatic switch throwing means including an operating member, a latch trip device pivotally connected with said operating member so as to have movement independently thereof, a second latch device for coupling the 105 trip device to the operating member, means for normally holding the second latch device inoperative, and a manually operable switch throwing device for controlling said trip device independently of the automatic switch 110 throwing mechanism.

14. In a railway switch, a self-closing switch point, a throw bar having a lost-motion cushioning connection with the switch point, a latch device for locking the throw bar in switch opening and closing positions, switch throwing means including an operating member, a trip device movably connected therewith, means for permitting said trip device to have advancing movement in co-operation with or independently of said operating device and for automatically returning the same to normal position after independent advancing movement, and means for operating said trip device independently of 120 said operating member.

15. In a railway switch, a self-closing switch point, a throw bar having a lost-motion cushioning connection with the switch point, a latch for locking the throw bar in 125

switch opening and closing positions, switch throwing means including an operating member, a latch trip device pivoted to said operating member so as to have an advancing movement with or independent of said operating member, means for retracting the trip member after independent actuation, means for coupling the trip member to the operating member for joint retraction after actuation, said means being inoperable when the parts are in normal position and thrown into operation upon an advancing motion thereof, and separate and independent means for actuating the trip device on its independent advancing motion.

16. In a railway switch, a self-closing switch point, a throw bar having a lost-motion cushioning connection with the switch point, switch throwing means including a swinging operating member, a pivoted latch trip device carried by said member, a latch controlled by said trip device for locking the switch bar in switch opening and closing positions, a second latch device, normally held retracted, for coupling the trip device to the operating member for retraction therewith when said members are jointly advanced, and means for returning the trip member to normal position after actuation when independently advanced.

17. In a railway switch, a self-closing switch point, a throw bar having a lost motion cushioning connection with the switch point, switch throwing mechanism including an operating member, a swinging latch trip device carried by said operating member, latch controlled by said device for locking the throw bar in switch opening and closing positions, separate and independent means for advancing the trip device independently of the first-named means, a latch for connecting the trip device with the operating member for retraction when said elements are jointly advanced, and a spring for permitting independent advancing movement of the trip device and subsequently retracting the same.

18. In a railway switch, a self-closing

switch point, a reciprocating switch throw bar having a lost motion cushioning connection with the switch point, a latch device for locking the bar in switch opening and closing positions, switch throwing means including an operating member, separate and independent switch throwing means including another operating member, a latch trip device operable independently by said members and carried by the first-named member, a latch for coupling said trip device to the first-named member for retraction therewith when said elements are advanced together, means for holding said latch retracted when the parts are in normal position, and a spring tensioned by the independent advancing movement of the trip device for returning it to normal position.

19. In a switch throwing device, a self-closing switch point, a throw bar having a lost motion cushioning connection with the switch point, a laterally movable guard rail, an actuating rod controlled by said rail and movable longitudinally in a general direction parallel with the track way, a latch device for locking the throw bar in switch opening and closed positions, a horizontally and laterally swinging member actuated by the rod, and a trip device controlled by said member for controlling said latch device.

20. In a railway switch, switch throwing mechanism including a laterally movable guard rail, a longitudinally movable actuating rod or bar, actuating connections between said parts, and retracting devices, each including a cylinder and a spring actuated piston therein, and a swing lever fulcrumed at one end to a fixed support and pivotally connected at its opposite end with the rail, said lever being pivotally connected with the piston rod at a point between the center and fulcrum end of the lever.

In testimony whereof I affix my signature in presence of two witnesses.
